US00D896518S

(12) **United States Design Patent** (10) **Patent No.:** **US D896,518 S**
Brunner et al. (45) **Date of Patent:** **** Sep. 22, 2020**

(54) **TOOL BOX**

(71) Applicants: **Keter Plastic Ltd.**, Herzelyia (IL);
Milwaukee Electric Tool Corporation,
Brookfield, WI (US)

(72) Inventors: **Yaron Brunner**, Kibbutz Gvat (IL);
Omer Menashri, Kibbutz Afikim (IL);
Izhar Shani, Kibbutz Gvat (IL); **Uri Parizer**, Kibbutz Hukok (IL); **Grant T. Squiers**, Cudahy, WI (US)

(73) Assignees: **Keter Plastic Ltd.**, Herzelyia (IL);
MILWAUKEE ELECTRIC TOOL CORPORATION, Brookfield, WI (US)

(**) Term: **15 Years**

(21) Appl. No.: **29/703,781**

(22) Filed: **Aug. 29, 2019**

Related U.S. Application Data

(62) Division of application No. 29/613,377, filed on Aug. 9, 2017.

(51) **LOC (12) Cl.** **03-01**

(52) **U.S. Cl.**

USPC **D3/294**

(57) **CLAIM**

The ornamental design for a tool box, as shown and described.

DESCRIPTION

FIG. 1 is a top perspective view showing our new design for a tool box;

FIG. 2 is a top plan view of the tool box of FIG. 1;

FIG. 3 is a front elevational view of the tool box of FIG. 1;

FIG. 4 is a rear elevational view of the tool box of FIG. 1;

FIG. 5 is a right side elevational view of the tool box of FIG. 1;

FIG. 6 is a bottom plan view of the tool box of FIG. 1; and, FIG. 7 is a bottom perspective view of the tool box of FIG. 1.

The translucent grey overlay and the broken lines in the drawings depict portions of the tool box that form no part of the claimed design.

1 Claim, 7 Drawing Sheets
